UNITED STATES PATENT OFFICE.

ARTHUR F. POOLE, OF WHEELING, WEST VIRGINIA.

HARMONIC SELECTIVE TELEPHONE SYSTEM.

1,070,726.

Specification of Letters Patent. Patented Aug. 19, 1913.

Application filed February 4, 1907. Serial No. 355,557.

To all whom it may concern:

Be it known that I, ARTHUR F. POOLE, citizen of the United States, residing at Wheeling, in the county of Ohio and State of West Virginia, have invented a certain new and useful Improvement in Harmonic Selective Telephone Systems, of which the following is a full, clear, concise, and exact description, reference being had to the accompanying drawings, forming a part of this specification.

My invention relates to party line selective telephone systems, its object being to provide simplified and improved selective means for enabling the selection of one party of a plurality of parties connected to a single telephone line.

For carrying out my invention, I employ harmonic selective devices at the substations adapted to respond to alternating currents of certain frequencies or characteristics, these devices being connected to control a circuit through the signal bells at the substations, and at the central exchange means are provided for sending alternating current or currents of certain frequencies into the line to cause actuation of the selective devices to set up current conditions for the bells at the substations to render one of the bells operative and the others inoperative, so that when ringing current from another source is simultaneously sent into the line, only the selected bell will ring. The selective devices for all the substations are identical, each having a plurality of contact sets, and the number of selective current generators at the central exchange is equal to the number of contact sets for each device. The contact sets of each device coöperate to control the circuit through the corresponding signal bell. Depending upon the combination of currents sent into the line from the central exchange, the contacts at the various substations coöperate when the selective devices are actuated to adjust the signal bell circuits to render one of the bells operative and to prevent operation of the others.

Broadly, the main feature of my invention resides in the use of harmonic selective currents in combinations, and in the use of selective devices at the substations responsive to such combination of selective current to control the signal bell circuits. With

this arrangement I am enabled to select from a far greater number of parties from a given number of frequencies over a single circuit than is possible in harmonic systems now in use in which the number of frequencies required is the same as the number of stations to be selected. This, of course, not only reduces the number of generators required at the central office but also the number of keys.

In the accompanying drawings I have illustrated my invention, and Figure 1 diagrammatically illustrates a telephone party line system showing the harmonic selective apparatus at the substations and circuit controlling apparatus at the central exchange; Fig. 2 is a top view of one of the harmonic selective devices which I may employ for the purpose of my invention; Fig. 3 is a side elevation of the selective device; Fig. 4 is an end view thereof, and Fig. 5 is a sectional view showing the relation of the contact springs to the armatures of the selective devices. Fig. 6 illustrates diagrammatically a modification involving eight subscribers' stations connected on a single line and the means for selectively signaling these stations in accordance with my invention.

The form of selective device shown is only one of the many which could be used for carrying out my invention and is shown as comprising the cores 1 and 2 connected by the yoke 3 and terminating respectively in pole blocks or shoes 4 and 5 having between them the air gap 6. On the cores 1 and 2 are mounted the energizing coils 7 and 8 respectively. An L-shaped polarizing bar 9 is secured at one end to the middle of the yoke 3, its other end being opposite the air gap 6 between the pole shoes, and from this end are supported the armatures 10 and 11 which extend into the air gap 6 normally midway between the pole faces. Ribs or springs 12 and 13 respectively connect the armatures 10 and 11 with the head 14 to which they are secured by means of the plate 15 and screws 16, this head extending through the bar 9 and secured thereto by the nut 17. These armatures are tuned to be responsive to alternating current flow through the coils of certain frequencies, and the armatures, therefore, may themselves be of different mass or weight, or weights 18

may be provided for the armature 10 and adjustably mounted on the threaded rod 19 extending therefrom, and weights 20 may be provided for the armature 11 and adjustably mounted on the threaded stem 21 extending therefrom. These weights, as shown, are doubled so that they may mutually lock each other to the threaded stems when the proper adjustment or tuning has been accomplished. Supported on the bar 9 below the armatures is an insulating mounting block 22 from which extend a set of contact springs 23^a, 24^a and a set of contact springs 25^b, 26^b, the contact springs of each set being normally in contact at their upper ends at which platinum contact points 27 and 28 respectively are provided. Abutment posts or washers 29, 30 are inclosed between the contact springs 23^a, 24^a and the upper armature 10 and may be carried by the armature or by the springs as shown. Similar abutment posts or washers 31 and 32 are interposed between the contact springs 25^b and 26^b and the lower armature and may be supported from the springs, as shown, these washers or posts being all of insulating material to insulate the springs from the armatures. A rod 33 of insulating material is secured at one end to the upper end of the bar 9, and the other end is secured to the non-magnetic bridge piece 34 spanning the pole shoes, and this bar is disposed between the ends of the contact springs of the sets so that when an armature is vibrated, the springs of the corresponding set will be repeatedly disconnected from each other,—that is, when the armature moves in one direction, one spring will be moved therewith, but the other spring will be stopped by the insulating bar 33, and thus contact between the springs broken, and in the same manner when the armature moves in the opposite direction, the other spring will be moved therewith and the first spring held by the insulating bar. Thus, when current of a certain frequency flows through the energizing coil, the upper armature will be vibrated to repeatedly disconnect the springs in the corresponding set, while, if a current of a different certain frequency flows through the energizing coil, the lower armature will be vibrated to repeatedly open the springs of the corresponding set. Both armatures, it will be noticed are controlled by the same set of energizing coils and instead of only two armatures being thus controlled, as shown, any number may be controlled by the same energizing coils upon current flow of different frequencies therethrough to which the various armatures are tuned.

In Fig. 1 I have shown the line limbs *x*, *y* of a telephone line leading from a central exchange E to the substations 1, 2, 3 and 4.

At the central exchange are shown the 65 spring contacts 35 and 36 connected with the line limbs, and the contact 37 is normally in engagement with the spring 35, and the limb *y* normally connects through these contacts and the indicator 38 with one pole of 70 the common central battery 39, the line limb *x* connecting directly with the other terminal of this battery. At each substation is shown a receiver switchhook 40 for supporting a receiver 41 and normally engaging 75 the contact 42. A signal bell 43 has two windings 44 and 45 having each a terminal connected with the contact 42. The harmonic selective device described in detail in Figs. 3, 4 and 5, is here diagrammatically 80 shown. One terminal of the selective energizing winding connects through conductor 46 with the contact 42, and the other terminal connects with conductor 47 with the line limb *y*, the switchhook 40 connecting 85 through conductor 48 with the line limb *x* so that normally the selective energizing coils at the substations are connected in bridge of the line limbs. A condenser 49, however, is inserted to be in circuit both 90 with the selective energizing coil and the windings of the signal bell at each substation. A transmitter 50 and primary winding 51 connect the line limb *y* with the switchhook when the switchhook is raised, 95 and the receiver is included in a local circuit including the secondary winding 52. At substation 1, the lower terminal of the signal bell winding 44 connects with the contact 25^b normally engaging the contact 26^b 100 which connects with the contact 23^a normally connected with the conductor 47. The other winding 45 of the signal bell is not utilized in this arrangement. At substation 2 the terminal winding 44 connects 105 both with contacts 25^b and 23^a, while the terminal of the winding 45 connects only with contact 24^a while contact 26^b connects with conductor 47, the upper terminals of the windings 44 and 45 being connected together and with contact 42, the same as at substation 1. At substation 3 the lower terminal of the signal bell winding 44 connects both with contacts 26^b and 23^a, while the lower terminal of winding 45 connects with 115 contact 25^b and contact 24^a connects with conductor 47. At substation 4 the lower terminal of winding 44 connects with contact 26^b and with conductor 47. The lower terminal of winding 45 connects with contacts 25^b and 23^a. At the central station is shown the cord circuit C terminating in the answering plug 53 and calling plug 54, and includes an operator's listening key 55 and selective keys 56^a, 57^b and 58^c. Upon depression of the operator's key 55, the operator's telephonic apparatus 0 will be connected in bridge of the cord circuit in a well 120 125

known manner. A ringing generator G either directly or through a transformer 59 connects with the alternate contact 60 of key 58^g and with contact 61 normally engaging spring 62 of key 57^b. The generator G may be any ordinary ringing generator of alternating currents such as is commonly used in telephone exchanges for ringing bells on single subscribers' lines. Spring 62 connects with contact 63 normally engaging spring 64 of key 56^a which spring connects with alternate contact 65 of key 58^g. Thus when key 58^g is depressed, current flows from generator G directly to the tip strand and serially through the selective key contacts to the sleeve strand of the calling plug. Between the normal contact 63 and alternate contact 65' of key 56^a is connected a selective current generator 66^a either directly or through a transformer 67. Between normal contact 61 and alternate contact 68 of key 57^b is connected a selective generator 69^b either directly or through a transformer 70. The generators 66^a and 69^b deliver currents of different character. In the preferred embodiment of my invention herein shown the generator 66^a delivers an alternating current of one frequency, this frequency being such as to affect the *a* contacts when flowing through the selective energizing windings. The generator 69^b delivers an alternating current of a different frequency and such that it will affect the *b* contacts when flowing through the selective energizing windings. These frequencies are such that current from the generator 66^a will not affect the *b* contacts nor will current from the generator 69^b affect the *a* contacts. The frequencies of the currents delivered by the selective generators are different from that delivered by the straight generator G. The alternating current delivered by the generator G will not, therefore, affect the contacts *a* or *b* which are tuned to respond to currents of the frequencies delivered by the special generators 66^a and 69^b. A supervisory indicator 71 may be connected between the battery and the cord circuit, as shown, for connecting the line limb *y* with battery when the connection through indicator 38 is broken upon insertion of the calling plug into the spring jack.

The operation of the system can now be readily understood, and for convenience I shall refer to keys 56^a, 57^b and 58^g as the *a*, *b* and *g* keys respectively; generators 66^a, 69^b and G I shall refer to as the *a*, *b* and *g* generators respectively; and the contact sets 23^a, 24^a and 25^b, 26^b I shall refer to as the *a* and *b* contacts. The spring jack at the right of the drawing is intended for connection with another line which it is not necessary to show here, it being supposed that a call comes in over this line, and in

response thereto the operator has inserted the plug 53 into the spring jack to ascertain the connection desired and that connection with the subscriber at substation 1 was desired. In response thereto, the operator inserted the calling plug 54 into the spring jack connected with the line limbs *x*, *y*, leading to substation 1 and other party substations connected with the line. The adjustment is such that the signal bell at substation 1 will respond only when the key 58^g at the central exchange is actuated to send only straight ringing current over the line from generator G. As described, the winding 44 of the signal bell at this substation is normally connected serially in circuit with the various contacts controlled by the selective energizing winding 7, but as the selective device will not respond to ordinary ringing current but only to the selective current from *a* or *b* generator, the *a* and *b* contacts will not be opened and consequently the circuit through the signal bell winding will not be opened, the result being that current from the *g* generator may flow through the signal bell to cause operation thereof. On the other hand, the signal bells at the other substations 2, 3, and 4 will not be affected. Neither will the selective devices at the other substations be affected. The contacts at these substations, therefore, will not be opened, but at substation 2, the windings 44 and 45 of the signal bell are connected in parallel and in opposition, the current flowing from line limb *x* through the hook switch contact 42 and condenser 49, part thereof passing through winding 44 to the common point 72, the remaining current flowing through winding 45 through the *a* contacts to the common point 72 which point connects through the *b* contacts and conductor 47 with line limb *y* and, therefore, this signal bell will not respond. At substation 3, part of the current from line limb *x* flows through winding 44 to the common point 72 and the remainder flows through winding 45 through the *b* contacts to the common point 72 which point connects through the *a* contacts and conductor 47 with line limb *y*. At substation 4 part of the current flows through winding 44 to the common point 72 and the remainder flows through winding 45 and through both contact sets *b* and *a* to the common point 72 and conductor 47 to line limb *y*, and the signal bell windings at the substations 2, 3 and 4 being in opposition, as before stated, the bells do not respond. Suppose now that connection had been desired with substation 2. The operator then depresses both the *g* key and one of the selective keys to simultaneously send current from the *g* generator and from the selective generator. Consider that the cur-

rent from the *a* generator is of such frequency as to affect the *a* contacts when flowing through the selective energizing windings and that current from the *b* generator affects the *b* contacts. The selective keys may be constructed to be locked when depressed in order to indicate what station is being selected. After the *a* key is depressed, the operator actuates the *g* key until the called subscriber answers. At substation 1 then, the current flow from the *a* generator through the selective winding 7 causes the *a* contacts to be opened, thereby preventing current flow from generator G through the signal bells which, therefore, do not respond. It might be stated here that the rapidity of vibration of the tuned armatures is sufficiently great so that, although in reality the contact springs of a set are rapidly opened and closed, the effect will be as though they were held open continually during vibration of the armature. At substation 2, however, the signal bell will respond as the selective device will respond to the current from the *a* generator to actuate the lower armature to open the *a* contacts, thereby opening the path through the winding 45 of the signal bell. Current from generator G then flows through line limb *x* through the winding 44 and through the *b* contacts to line limb *y*, the signal bell then sounding. At substation 3 the *a* contacts control both circuits through the signal bell windings, and upon being opened there will be no current flow through the signal bell. At substation 4, opening of the *a* contacts will have no effect on the signal bell, as the path through the *b* contacts remains closed and current from generator G flows through both windings 44, 45 of the signal bell, but as these windings are in opposition, there will be no response of the signal bell. Thus, when the *a* and *g* keys are both depressed, the signal bell at substation 2 only will be effective. If it had been desired to call substation 3, the operator would simultaneously actuate the *b* and *g* keys so that current from the *b* and *g* generators will flow simultaneously over the line. At substation 1, the signal bell will not ring because the *b* contacts are opened upon current flow through the selective device winding 7 from the *b* generator. At substation 2, the *b* contacts control both paths through the signal bell windings and when opened, there can be no current flow through the signal bell windings from generator G and consequently no response. At substation 3, the *b* contacts upon being opened, will disconnect winding 45 from circuit, leaving in winding 44 which will cause response of the signal bell. At substation 4, opening of the *b* contacts has no effect on the signal bell windings on account of the parallel circuit

through the *a* contacts, and on account of 65 the opposed relation of the windings, current flow therethrough will not cause response of the bell. If substation 4 was desired, the operator would simultaneously 70 actuate the *a*, *b* and *g* keys so that current from the generator G and from both selective generators will flow simultaneously 75 over the line. The currents from the *a* and *b* generators will cause operation at all the substations of the selective apparatus there- 80 at to open both contact sets. At substation 1, this prevents current flow through the signal bells which do not respond. At substations 2 and 3 there will also be no current flow through the signal bell windings, 85 but at substation 4 the parallel circuits controlling current flow through the winding 45 will both be opened and the remaining current flow through winding 44 will cause actuation of the signal bell. Thus, with 85 three ringing keys I am enabled to selectively call any one of four substations connected to a party line, the selective key or keys being first depressed to establish the proper circuit arrangement at the substations, and the ringing key 58^g then actuated to ring the bell at the selected substation. By the addition of one selective key and another source of selective current, the available combinations will enable me to 95 selectively connect any one of eight substations connected to the same party line, and with five keys I am enabled to selectively signal any one of sixteen substations connected with the same party line and so 100 on, each additional key doubling the previous number of substations. Each additional key, of course, calls for an additional armature for the selective devices at the substations.

Viewed from the standpoint of their position in the circuit, the various contact sets for each selective device are either operative or inoperative. By an operative contact is meant one which when opened will adjust 110 the associated bell circuit so that the bell may ring, as, for instance, the *a* contacts in station 2. By an inoperative contact is meant one which when opened will adjust the bell circuit to prevent the bell from 115 ringing, such as the *a* contacts at substation 1. The number of contact sets at each station is the same as the number of harmonic frequencies provided at the central office. The position of these contacts in the 120 signalling circuit of any substation is determined by the following law: If *n* is the number of harmonic frequencies provided and *m* is the number of operative contacts at any substation, then *n*—*m* will be the number of 125 inoperative contacts. I give here two tables, showing the position of operative and inoperative contacts for a four party line, as

shown in Fig. 1, and for an eight party line as diagrammatically illustrated in Fig. 6.

4 Party Combinations.

	Opr.	Inop.	Keys.
1		A-B	G
2	A	B	G+A
3	B	A	G+B
4	A-B		G+A+B

8 Party Combinations.

	Opr.	Inop.	Keys.
1		A-B-C-	G
2	A	B-C	G+A
3	B	A-C	G+B
4	C	A-B	G+C

6	A-C	B	G+A+C
7	B-C	A	G+B+C
8	A-B-C		G+A+B+C

Fig. 6 illustrates diagrammatically the application of my invention to an eight party line system. From the detailed description of the four party line arrangement, the eight party line system will readily be understood by those skilled in the art. In order to avoid unnecessary prolixity, I shall not follow this circuit in detail. Suffice it to say that the reference letters apply to similar parts in Fig. 6 as in Fig. 1. In addition to the G generator and the a and b generators and contacts associated with the cord circuit in Fig. 1, there is added in Fig. 6 a c generator with the associated transformer and ringing key. Eight substations are shown in place of the four substations of Fig. 1, and all of the selective magnets are equipped with additional armatures or reeds lettered 81^c tuned to respond to currents of the frequency of that delivered by the c generator. These additional armatures or reeds coöperate with contacts 82^c. The c generator, of course, delivers a current of a frequency different from the frequency of either of the other selective generators a or b and different from that of the straight generator G. The mode of operation of the eight party arrangement will be apparent from the detailed description of the operation of

the four party system and from the table 65 showing the position of the operative and inoperative contacts for the eight party line system.

To illustrate the formula, consider station 5 on the 8 party line table. Here n or 70 the number of harmonic frequencies required at the central station is 3, and m, the number of operative contacts is 2. Therefore, the number of inoperative contacts is n-m or 1. In other words, at substation 5 the 75 a and b contacts would be operative, and the third or c contact would be inoperative. At substation 1, all the contacts would be inoperative which means that the operation of any one or more thereof will prevent 80 ringing of the bell. For a sixteen party line, there will be four contact sets for each selective device and four frequency selective currents at the central exchange. At substation 1, the contacts would all be inoperative. At the second substation, contact a would be operative and the other contacts inoperative. At substation 3, contact b would be operative, and contacts a, c and d inoperative and so on. At substation 5, contacts a and b would be operative and contacts c and d inoperative and so on. This use of harmonic currents in combinations, I consider as being broadly new with me as also the use of ringing keys in various combinations for connecting the current sources with the line.

I do not wish to be limited to the arrangements herein shown nor to the exact construction of the selective device as shown. 100 The cord circuit arrangement is only one of the many arrangements which might be used for connecting the various signaling currents with the line. Changes in the substation arrangements could also be made without departing from the scope of my invention.

What I claim as new and desire to secure by Letters Patent is:

1. In a telephone system, the combination with the two limbs of a telephone line circuit leading from a central exchange to a substation, of a signal bell at the substation connected in bridge of the line limbs, an electromagnetic circuit controlling device 110 at the substation for controlling the circuit through the associated signal bell windings, the circuit controlling device being connected also in bridge of the said line limbs, and means at the central exchange for sending 115 current of different character simultaneously over the line, the circuit controlling device being responsive to current of one character and the signal bell being responsive to current of different character.

2. In a telephone system, the combination with a telephone line connecting a central exchange with a substation, of means at the

central exchange for sending currents of different character into the line, a signal bell at the substation, a circuit controlling device at the substation for the signal bell circuit, 5 said circuit controlling device being normally adjusted to prevent effective flow of current of one character through the signal bell, said controlling device being responsive only to current flow of different character 10 to change the circuit conditions to allow response of the signal bell to the first current flow.

3. In a selective signaling system, the combination with the two limbs of a line circuit 15 extending from a central office to a substation, of sources of current of different character located at the central office, means located at the central office for simultaneously connecting the line limbs with said sources 20 of current, an electromagnetic circuit controlling device responsive to current of the character delivered from one of said sources, said circuit controlling device being connected in bridge of the line limbs at the 25 substation, and a signal bell responsive to current of the character delivered from the other source, said signal bell being connected in bridge of the same line limbs through a circuit controlled by said circuit controlling 30 device.

4. In a telephone exchange system, the combination of a telephone line connecting a central exchange with a substation, sources of current of different character at the central exchange, means for connecting said sources with the line to cause current therefrom to flow simultaneously over the line limbs, a signal bell at the substation normally adjusted to be irresponsive to the current flow from one source, a circuit controlling device at the substation responsive to current flow from the second source to change the adjustment of the signal bell to allow actuation thereof by the current 45 flow from the first source.

5. In a telephone exchange system, the combination of a telephone line connecting a central exchange with a substation, sources of current of different character at the central exchange, means for connecting said sources with the line to cause current therefrom to flow simultaneously over the line limbs, a signal bell at the substation, a circuit controlling device at the substation, 50 windings for the signal bell normally included in a circuit bridging the line limbs but acting in opposition to prevent response of the signal bell to current flow from one of the sources, said circuit controlling device being responsive to current from the other source to rearrange the circuit conditions of the signal bell to allow actuation thereof by the current from the first source.

6. In a telephone exchange system, the

combination of a telephone line connecting a central exchange with a substation, sources of current of different character at the central exchange, means for connecting said sources with the line to cause current therefrom to flow simultaneously over the line limbs, a signal bell and a circuit controlling device at the substation, said signal bell having two windings normally connected in parallel branches with the line limbs and through contacts of the controlling device whereby said signal bell is normally irresponsive to current flow, said selective device being responsive to current flow from one of said sources only to move its contacts to change the circuit conditions of the signal bells whereby said signal bell may be responsive to current flow from the other source.

7. In a telephone exchange system, the combination of a telephone line connecting a central exchange with a substation, sources of current of different character at the central exchange, means for connecting said sources with the line to cause current therefrom to flow simultaneously over the line limbs, a circuit controlling device at the substation, a signal bell at the substation having two windings normally connected with the line limbs through parallel paths including contacts of the controlling device, said windings being in opposition so that the bell is normally irresponsive to current flow, said controlling device being responsive only to current flow from one of said sources to actuate its contacts to open one of the paths of the signal bell whereby said bell may respond to current flow from the other source.

8. In a party line telephone system, the combination of a telephone line leading from a central station to a plurality of substations, sources of current of different character at the central exchange and means for connecting said sources with the line, a signal bell at one substation having a winding normally included serially in a circuit connected with the line limbs, a signal bell at each of the other substations having two windings normally connected with the line limbs in parallel branches and in such manner that the windings act in opposition upon current flow therethrough whereby current flow from one of said sources will affect only the signal bell at the first substation, a circuit controlling device at the first substation having contacts included serially in the bell circuit, a circuit controlling device at each of the other substations having contacts included in the parallel branches of the bell circuit, said circuit controlling device being responsive to current flow from the other source, the device at the first substation, when actu-

ated, moving its contacts to open the bell circuit and the device at one of the other substations being actuated to move its contacts to disconnect one of the signal bell windings 5 from circuit whereby when said sources are simultaneously connected with the line, only the signal bell at the other substation will be actuated.

9. In a telephone exchange system, the 10 combination of a telephone line extending from a central exchange to a plurality of substations, sources of current of different character at the central exchange adapted for connection with the line, a signal bell at 15 the first substation normally connected with the line limbs, a circuit controlling device at the first substation for normally controlling the signal bell circuit to render the signal bell operative, a signal bell at each of the 20 other substations connected with the line, a circuit controlling device at each of the other substations normally controlling the signal bell circuits to render the signal bell inoperative, said controlling device being responsive 25 to current from only one of said sources, the signal bell at the first substation being actuated upon current flow from the other source, and means adapted upon current flow from the first source to actuate the controlling device at the first substation to render the signal bell inoperative and to cause 30 actuation of the controlling device at one of the other substations to rearrange the signal bell circuit to render the signal bell operative 35 whereby current flow from the second source will cause actuation of the signal bell only at one of the other substations.

10. In a telephone exchange system, the 40 combination of a telephone line connecting a central station with a plurality of substations, a source of ringing current at the central station adapted for connection with the line, a source of selective current at the central station also adapted for connection with 45 the line, a circuit controlling device at one of the substations and a signal bell thereat whose winding is normally connected serially with the line limbs and through contacts of the controlling device, a selective 50 controlling device at the other substation, a signal bell at the second substation having two windings normally connected in parallel paths with the line limbs through contacts of the controlling device and in a direction 55 to be in opposition upon current flow therethrough, said controlling device being responsive only to current flow from the selective source, current flow from the source of ringing current alone causing actuation only 60 of the signal bell at the first substation and simultaneous current flow from both sources causing operation of the controlling device at the first substation to open the circuit through the bell and operation of the con-

trolling device at the second substation to 65 break the parallel opposite relation of the signal bell windings whereby the current flow from the ringing source will actuate only the bell at the second substation.

11. In a telephone exchange system, the 70 combination of a telephone line connecting a central exchange with a plurality of substations, a plurality of sources of selective current of different character at the central exchange adapted for connection with the 75 telephone line, a selective circuit controlling device at each substation, sets of contacts for each one of said devices independently responsive to current flow of one character through the device, a signal bell at each substation connected with the line limbs through 80 circuits controlled by the contact sets, said circuits being normally adjusted to cause the signal bells to be inoperative, said selective devices being connected with the line limbs, 85 current flow through the line from one of said sources causing actuation of the corresponding contact sets at one of the substations only to rearrange the circuit conditions to render the signal bell operative, and a 90 source of ringing current at the central exchange adapted for connection with the line when the source of selective current is connected therewith whereby the selected signal bell is operated.

12. In a telephone exchange system, the 95 combination of a telephone line connecting a central station with a plurality of party line substations, a plurality of sources of selective current and a source of ringing current 100 at the central exchange adapted for connection with the line, a signal bell at each substation having two windings normally connected in parallel and in opposition so that the bell is irresponsive to current flow from the ringing generator, an electromagnetic controlling device at each substation having a number of contact sets equal to the number of selective sources at the central station, each set actuated only upon current flow 105 through the device from the corresponding source of selective current, circuits for the signal bells of each substation normally including the contacts of the controlling device, current flow from one of said selective 110 sources causing actuation of the controlling devices at the substations and actuation of the corresponding contact sets, the signal bell circuit arrangement at only one of the substations being rearranged upon actuation 115 of the contact set thereat to render the signal bell operative whereby current flow from the source of ringing current may operate said bell.

13. In a telephone exchange system, the 120 combination with a pair of conductors, of a plurality of substations connected therewith, 125 signaling apparatus at each substation,

- sources of alternating electromotive force of different frequencies adapted to be impressed upon said conductors in various combinations, and means at each substation 5 for rendering the associated signaling apparatus responsive to some particular combination of said electromotive force.
14. In a telephone exchange system, the combination with a pair of conductors, of a 10 plurality of substations connected therewith, signaling apparatus at each substation, sources of alternating electromotive force of different frequencies adapted to be impressed upon said conductors in various 15 combinations, and means at each substation for rendering the associated signaling apparatus responsive to some particular combination of said electromotive force and irresponsive to all other combinations.
15. In a telephone system, the combination with a central exchange, of a pair of conductors leading from the central exchange to a plurality of substations, a signal bell at each substation included in a normally 20 closed circuit in bridge of the line limbs, sources of alternating selecting currents of different frequencies at the central exchange, means at the central exchange for connecting said sources of selecting currents 25 of different frequencies in various combinations with the line, a selective device at each substation, each responsive to a certain combination of currents delivered from said sources of selecting currents and each controlling 30 a circuit of the corresponding signal bell, and a source of ringing current at the central exchange adapted for connection with said pair of conductors simultaneously with the connection of the source or sources 35 of selecting currents.
16. In a selective signaling system, the combination with a pair of conductors connecting a central office with a plurality of substations, of sources of selective currents 40 of different character located at the central exchange, means located at the central exchange for connecting said sources with said pair of conductors in various combinations, a selective device at each substation, a signal bell at each substation, each signal bell being 45 connected in bridge of the pair of conductors through a circuit controlled by the associated selective device, each selective device being actuated to establish an inoperative 50 condition in the associated signal bell circuit when actuated by any combination of selective currents except one, and a source of ringing current at the central office adapted for connection with said pair of conductors simultaneously with the connection of 55 said sources of selective currents to actuate the selected signal bell.
17. In a telephone system, the combination with a telephone line connecting a cen-

- tral exchange with a plurality of substations, of a signal bell at each substation, sources at the central exchange for supplying selective currents of different character, means at the central exchange for connecting said sources with the line in various 60 combinations, a selective device at each substation responsive in different ways to different combinations of selective currents sent over the line, each selective device controlling the circuit for the corresponding 65 signal bell, a certain combination of selective currents sent over the line causing actuation of only one of the selective devices to render the corresponding signal bell operative and causing actuation of all the other 70 devices to hold the corresponding signal bells in inoperative condition, and a source of ringing current at the central exchange adapted for connection with the line to cause 75 ringing of the selected signal bell.
18. In a telephone exchange system, the combination with a line connecting a central exchange with a plurality of substations, of a signal bell at each substation, a plurality 80 of sources at the central exchange for supplying selective currents of different frequencies, means for connecting said sources with the line in various combinations, a selective device at each substation having a plurality of contacts mutually controlling 85 the circuit of the corresponding signal bell, a certain combination of selective currents sent into the line causing operation of the selective devices at the substations to actuate the corresponding contacts so that at one 90 substation only the contacts will be actuated to adjust the signal bell circuit to render the signal bell operative and so that at the other substations the contacts will be actuated to maintain the signal bells inoperative, and 95 a source of signaling current at the central exchange adapted for connection with the line to send signaling current through the selected signal bell.
19. In a telephone system, the combination with a telephone line connecting a central exchange with a plurality of substations, of a signal bell at each substation, sources at the central exchange for supplying selective currents of different character, 100 means for connecting said sources in various combinations with the line, an electromagnetic device at each substation having two armatures, each responsive to one of the 105 selective currents, the contacts controlled by each armature and the contacts of each device co-operating to control the circuit for the corresponding signal bell, a certain combination of selective currents sent into the line causing actuation of the corresponding 110 armatures of the selective devices, the resultant arrangement of the contacts at only 115 one of the substations being such that the 120
- 125

corresponding signal bell circuits are arranged to render the signal bell operative and the arrangement of the contacts at the other substations are such that the signal 5 bells are maintained in inoperative condition, and a source of ringing current at the central exchange adapted for connection with the line to send ringing current through the selected signal bell.

10 20. In a selective signaling system, the combination with a plurality of stations connected with a pair of conductors, of a signal bell at each station, a plurality of sources of selective currents of different frequencies 15 adapted for connection with said pair of conductors, means for connecting two or more of said sources of selective currents simultaneously with said pair of conductors, a selective device at each station having a 20 plurality of contacts mutually controlling the circuit of the corresponding signal bell, the selective devices at the substations being responsive to various combinations of selective current flow to render one of the signal 25 bells operative and the other signal bells inoperative, and a source of ringing current adapted for connection with said pair of conductors for supplying ringing current to ring the selected signal bell.

30 21. In a selective signaling system, the combination with a plurality of stations connected with a pair of conductors, of a signal bell at each station, a plurality of sources of selective currents of different frequencies 35 adapted for connection with said pair of conductors, means for connecting two or more of said sources of selective currents simultaneously with said pair of conductors, and a selective device at each station having a 40 plurality of contacts mutually controlling the circuit of the corresponding signal bell, the selective devices at the substations being responsive to various combinations of selective current flow to render one of the signal 45 bells operative and the other signal bells inoperative.

22. In a telephone system, in combination, a plurality of tuned reeds, electromagnetic means for actuating said reeds, and a telephonic signaling instrument controlled in its 50 operation by said reeds jointly.

23. In combination in a telephone system, a series of stations, a plurality of differently tuned reeds at each station, an electromagnet 55 for vibrating the reeds at said stations, means for impressing electromotive forces of different frequencies upon each electromagnet in various combinations, and telephonic signaling mechanism at each station whose 60 operation is controlled by said reeds.

24. In combination in a telephone system, a series of stations, a plurality of differently tuned reeds at each station, electromagnets for vibrating the reeds at said stations,

means for impressing electromotive forces 65 of different frequencies upon said electromagnets in various combinations, and a telephonic signaling instrument at each station controlled in its operation by said reeds jointly.

25. In combination, a series of stations, a plurality of differently tuned reeds at each station, electromagnets for vibrating the reeds at said stations, means for impressing electromotive forces of different frequencies 75 upon said electromagnets in various combinations, a signaling device at each station controlled in its operation by said reeds jointly, and a signal bell circuit at each station jointly controlled by the reeds at said 80 station.

26. In combination in a telephone system, a series of stations, a plurality of differently tuned reeds at each station, electromagnets for actuating said reeds, a common circuit 85 for supplying current to said electromagnets, means for impressing electromotive forces of different frequencies upon the electromagnet circuit in various combinations, and a telephone bell at each station whose 90 connection with the electromagnet circuit is controlled by the associated reeds.

27. In combination, a series of stations, a plurality of differently tuned reeds at each station, electromagnets for actuating said 95 reeds, a common circuit for supplying current to said electromagnets, means for impressing electromotive forces of different frequencies upon the electromagnet circuit in various combinations, a signaling device 100 at each station controlled in its operation by said reeds jointly, and a special source of current for actuating the signaling devices.

28. In combination, a series of stations, a plurality of differently tuned reeds at each 105 station, electromagnets for actuating said reeds, a pair of conductors in bridge of which the electromagnets are connected, sources of electromotive forces of different frequencies adapted to be impressed upon 110 said conductors in various combinations, and an electric signaling device connected in bridge of said conductors at each station, the circuit of each signaling device being controlled by the associated reeds.

29. In a selective signaling system, the combination with a series of stations, a plurality of differently tuned reeds at each station, electromagnets for actuating said reeds, a pair of conductors in bridge of which said 120 electromagnets are connected, sources of alternating electromotive forces of different frequencies adapted to be impressed upon said conductors in various combinations, the vibration rate of the reeds at each station 125 corresponding with the frequencies of said sources, an electric signaling device at each station included in a circuit in bridge of said

conductors, the circuit of each signaling device being controlled by the associated reeds whereby a particular signaling device is operatively connected in bridge of said conductors to correspond with the connection of each combination of alternating electro-motive forces in the circuit, and a separate source of current adapted for connection with said conductors to operate the signaling devices.

30. In combination, a plurality of differently tuned reeds, common electromagnetic means for vibrating the reeds, means for directing currents of different character through the electromagnetic means to cause selective operation of the reeds, and electrically operated mechanism adapted to be controlled in its operation by such reeds jointly.

31. In combination, a plurality of tuned 20 reeds, a common electromagnetic means for vibrating the reeds, means for directing currents of different character through the electromagnetic means to cause selective operation of the reeds, and signaling mechanism 25 adapted to be controlled in its operation by said reeds jointly.

32. In combination, a plurality of tuned reeds, a common electromagnetic means for vibrating the reeds, sources for producing current flows of different frequencies, means for selectively connecting said current flows with the electromagnetic means to cause vibration of the correspondingly tuned reeds, and signaling mechanism adapted to be controlled by said reeds jointly.

33. In combination, a plurality of tuned reeds, a common electromagnet for vibrating the reeds, means for impressing electro-motive forces of different frequencies upon the electromagnet in various combinations to cause one of the reeds to be selected and vibrated, a signaling circuit controlled by each reed, and a signaling instrument adapted to be controlled in its operation by said reeds jointly.

In witness whereof, I hereunto subscribe my name this 21st day of January, A. D., 1907.

ARTHUR F. POOLE.
